US0D1033637S

(12) **United States Design Patent** (10) **Patent No.:** **US D1,033,637 S**
(45) **Date of Patent:** **** Jul. 2, 2024**

(54) **FLUID EXCHANGE DEVICE**

(71) Applicant: **Genentech, Inc.**, South San Francisco, CA (US)

(72) Inventors: **Joshua David Horvath**, San Ramon, CA (US); **Kristof Hovaten**, South San Francisco, CA (US); **Daniel Douglass**, South San Francisco, CA (US); **Keith Bianchi**, South San Francisco, CA (US)

(73) Assignee: **ForSight Vision4, Inc.**, South San Francisco, CA (US)

(**) Term: **15 Years**

(21) Appl. No.: **29/824,354**

(22) Filed: **Jan. 24, 2022**

(51) LOC (14) Cl. **24-02**

(52) U.S. Cl.

USPC **D24/130**; D24/112; D24/150

(58) **Field of Classification Search**

USPC D24/127-131, 133, 186, 110, D24/110.1-110.6, 113, 108

CPC A61M 16/0816; A61M 16/0875; A61M 39/105; A61M 2016/003; A61M 2039/1088

See application file for complete search history.

(57) **CLAIM**

The ornamental design for a fluid exchange device, as shown and described.

DESCRIPTION

FIG. 1 is a bottom, front, and right side perspective view of a fluid exchange device of our design;

FIG. 2 is a top, front, and left side perspective view thereof;

FIG. 3 is a bottom, rear, and right side perspective view thereof;

FIG. 4 is a right side view thereof;

FIG. 5 is a left side view thereof;

FIG. 6 is a rear view thereof;

FIG. 7 is a front view thereof;

FIG. 8 is a bottom view thereof;

FIG. 9 is a top view thereof;

FIG. 10 is an enlarged view taken from FIG. 1; and,

FIG. 11 is an enlarged view taken from FIG. 2.

The dash-dash broken lines illustrate portions of the fluid exchange device that form no part of the claimed design.

1 Claim, 6 Drawing Sheets
